UNITED STATES PATENT OFFICE.

ELISHA JESSE CADY, OF CHICAGO, ILLINOIS.

SATURATION OF POROUS FABRICS.

1,268,430.

Specification of Letters Patent.

Patented June 4, 1918.

Application filed April 2, 1917. Serial No. 159,120.

To all whom it may concern:

Be it known that I, ELISHA JESSE CADY, a citizen of the United States, residing at Chicago, in the county of Cook and State 5 of Illinois, have invented certain new and useful Improvements in Saturation of Porous Fabrics, of which the following is a specification, reference being had therein to the accompanying drawing.

10 My invention relates to the saturation of porous fabrics, such as paperboard, strawboard, or paper felt used in the manufacture of building paper, artificial shingles, and the like, and it consists in the novel 15 method of saturating the same with a suitable solution of asphalt or kindred products, as hereinafter set forth and pointed out in the claims.

In saturating stock of this character, 20 especially where the product is to be used in places exposed to heat or the sun, uniform saturation is necessary as otherwise the product will warp, and as such warping destroys its value the importance of eliminating this defect is vital. When immersed 25 in a hot bath of saturating solution the air in the layers or pores or pockets of the stock is trapped and expands under the heating action of the solution, and gases are generated and similarly trapped, and both of 30 these conditions cause the material to puff, so that the saturation is uneven and the product will subsequently warp or blister. Similarly moisture in the stock will cause it 35 to unevenly take up the solution, and steam arising from the moisture by the heat of the bath will cause it to puff and swell, and both of these factors tend to produce unevenness in saturation. Also, where portions 40 of a strip of stock are unequally subjected to the saturating action of a solution some are either unsaturated or only unevenly or partly saturated and so destroy the homogeneity of the product; for this 45 reason uniformity of saturation of all linear portions of a strip is desirable. Furthermore, in saturating stock of this character, moistening the stock by the solution softens its fibers and loosens them from each other 50 so that the surface is susceptible to ruptures and abrasions and the texture or body is liable to tear or break, and hence continuity of saturating action is desirable as then the draft on the stock is steady so that its surface 55 is less liable to disturbance and its

body is not subjected to intermittent or sudden strains or pulls.

By my invention I uninterruptedly subject one surface of a length or strip of the stock to the stress or pressure of the weight 60 of a body of the saturating solution while the opposite surface of the stock is free from direct contact with the solution, and preferably while this opposite surface is in the presence of a reduced air pressure that 65 tends to draw the solution applied to its other surface through the stock. The pressure or stress of the weight of the solution positively forces the latter into the stock and also expels from the stock all air, moisture 70 and gases which thereby are forced out of its unobstructed opposite surface, so that the solution may freely and uniformly enter the stock and the latter is uniformly saturated and filled up and without trapping 75 any air, gas or moisture, and so without forming any puffs or warps or blisters or other deteriorating conditions; and the suction through the stock created by the reduced air pressure at its free side or surface expedites the evacuation of the air, moisture and gases as it draws them out, and it also expedites the saturation as it draws the solution into the stock. By subjecting one surface of the stock to the 80 weight of the body of the solution the latter is put into an effective condition to utilize the pressure or stress of the solution itself as the saturating or penetrating force, and also to utilize this functional or working 85 capacity of the solution itself in an uninterrupted manner to permit a strip of stock to be moved in its presence to insure, first, homogeneity of saturation of all its linear portions so that no cross-sectional 90 portion is either unsaturated or only partially or unevenly saturated, and second, continuity of the saturating action on the strip so that the moistened stock may be steadily moved and not subjected to intermittent or sudden strains or pulls. Also, 95 the surface of the stock is not subjected to any rupturing or abrading agencies or influences.

By my invention the saturation of paperboards or paper felts of different degrees of density by asphalt or like solutions is positively effected and so is completed in less time than by the capillary processes heretofore employed, and it is uninter- 100 105 110

ruptedly effected to assure both continuity and homogeneity of saturation of a length or strip of stock.

My invention, briefly stated, consists in 5 subjecting one surface of the traveling stock to the weight of a body of asphalt solution and maintaining the opposite surface of the stock free from direct contact with the solution, and preferably while the opposite surface 10 is in the presence of or subjected to a reduced air pressure or partial vacuum to draw the liquid into the stock.

The solution or compound of asphalt is prepared in any usual way now well known 15 in the art for saturating or coating paper-board or felt, and is contained in a suitable tank or vessel in such known consistency that it will soak into the stock. One side or face of the stock is subjected to the direct and continuous action of the weight of 20 the liquid by moving it slowly and at approximately uniform speed in the tank with that side or surface in contact with a suitable head or column of the liquid and with 25 the other side or surface of the stock free from contact with the liquid and preferably in the presence of a reduced air pressure or partial vacuum, so that all portions are subjected to the evacuating influences or factors 30 and also are uniformly and directly subjected to the positive soaking or impregnating action of the solution. This is accomplished, preferably, by moving the stock on a perforated body located in the tank having 35 its ends closed and of such size as to allow one surface of a section of the stock on the body to be directly exposed to the weight of the liquid, so that the various portions or sections of the stock are exposed 40 to the stress or pressure of the liquid for approximately uniform periods of time, and are homogeneously saturated, and the saturating action is continuous for the run of the strip of stock so that it can be moved 45 steadily to eliminate sudden or intermittent strains or pulls on its body weakened by the moisture of the solution, and also without abrasions, breaks or scores in its surface. After being saturated with the asphalt compound or solution the stock is removed 50 from the bath and allowed to dry and harden or set.

My invention may be carried out in a variety of ways and by various means, and 55 in order to clearly illustrate the preferred manner of practising it, I represent in the accompanying drawings an apparatus for carrying it out, though I do not specifically limit myself to said apparatus, which may 60 be of any suitable construction for the purpose intended.

In the drawing Figure 1 represents a longitudinal sectional view on the line 1-1 of Fig. 2 showing a tank or vessel containing 65 a liquid solution or compound of asphalt and

a perforated drum over which the stock is passed and in which a reduced air pressure may be provided;

Fig. 2 is a cross-sectional view of the parts of Fig. 1; 70

Fig. 3 is a detail sectional view of the perforated body of the drum;

Fig. 4 is a view similar to Fig. 1 and showing a modified form of the apparatus;

Fig. 5 is a cross-sectional view of the parts of Fig. 4, on the line 5-5, and 75

Fig. 6 is a detail view partly in section of parts of Fig. 4.

The same reference letters refer to the same or similar parts in the different views. 80

In the drawing the reference letter A represents the tank or vessel of general rectangular shape containing the liquid asphalt solution or compound. The sides a of the tank are preferably curved at their bottom portions to provide a container of the general contour shown, and the ends a' of the tank are closed. The tank is provided at its top with a supply pipe a² for the saturating solution or compound, and at its bottom with an outlet a³ by which the solution may be drawn off and the tank emptied. It is also provided with a steam-jacket B in which steam is diffused by any suitable means to heat the liquid content of the tank to the required temperature, say 300° to 400° Fahrenheit, only a single steam inlet b being shown for simplicity of illustration, and a drain b' is provided for the products of condensation in the steam-jacket. The tank and its jacket are carried by a suitable frame C.

The tank in the form shown in Figs. 1 and 2 is also provided with a drum D having a perforated body and mounted on a revolving shaft d which is supported centrally across the tank in suitable bearings having the usual stuffing-boxes, and has a drive gear d' at one of its projecting ends

to revolve the shaft and drum from any suitable source of power, as from the drive-pinion d² on the drive shaft d³. The periphery or body of the drum is perforated, and preferably it is composed of foraminous material, such as wire-mesh; in the present

instance it is composed of an outer layer of relatively fine wire-mesh and an inner layer of relatively coarse wire-mesh as shown in Fig. 3. The body of the drum is supported in position on the shaft by a series of spaced inner rings d⁴ carried by corresponding spiders d⁵ fixed to the shaft. The drum is closed at one end by an imperforate head d⁶, and at its other end its extreme ring d⁴ makes a liquid-tight slip joint with an annulus d⁷ of corresponding diameter fixed to the inner edge of an annular recess or chamber formed by outwardly extending or offsetting the corresponding portion of the associated end a' of the tank, as shown at a⁸ 130

110
115
120
125

in Fig. 2. The recess or chamber substantially forms a continuation of the inner area of the drum so that the latter is closed except through its perforated body, and this 5 chamber is provided at its bottom with a pipe a^6 leading to a suitable exhaust-pump P by which the solution may be drawn out of the drum and the air pressure in the drum may be reduced when it carries a 10 length of stock.

The tank is provided with a traveling endless belt or apron E of wire mesh, whose width is approximately the length of the drum, and this apron passes over suitable 15 guide-rollers, with its working stretch or run against the outer surface of the drum for the major portion of its circumference. The apron passes over a pair of drive rollers e extending preferably across the central 20 portion of the top of the tank and through its end walls where they are carried in suitable bearings on the frame, the rollers being disposed so that their upper portions are above the level of the liquid in the tank, 25 and being driven by any suitable means to move the operative run or portion of the apron in the same direction as and in unison with the drum; the drive rollers may be driven from the gear-wheel a' by suitable 30 gear-pinions e' . The tank is also provided with front and rear guide rollers e^2 and e^3 , respectively, on the level of the drive rollers and one on each side thereof, and with two 35 pairs of opposite guide rollers e^4 and e^5 , respectively, located at different levels in the tank and so disposed as to guide the apron with its working run in position against the drum and its idle run spaced from the working run. The apron is not essential, but it 40 is desirable when the material under treatment is liable to break or split as then it carries the broken ends around and out of the tank.

The tank is provided with a cover G 45 which has inlet and outlet passages for the material adjacent the rollers e , and the central portion G' of the cover between these rollers is constructed to make tight joints with the rollers when the material is in position therebetween and also to close the drum between the extremities of a length of material thereon. For these purposes the intermediate cover portion G' is provided with a bottom wall g which is curved in 50 cross-contour to correspond with the curvature of the drum and rests against or close to the face of the drum, and with opposite side walls g' which are curved in cross-contour to correspond with the rollers e to act 55 as guides for the stock, and the upper ends of the walls g' are carried tangentially away from the rollers to form inlet and outlet guide-lips g^2 for the stock. The wall g is beveled at its ends to extend more or less 60 between the drum and the extremities of the 65 length or portion of the material on the drum, and this doctor-wall and the rollers may be faced with felt or other material.

In carrying out my invention on this form of apparatus the end of a length of stock S 70 is fed into the machine until it enters the bite between the revolving drum and the apron on the initial guide roller e , as shown at the right hand of Fig. 1, the drum and apron being moved in unison in the direction 75 of the arrow until the end of the strip reaches the other roller e , when the machine is stopped. The tank is then filled with the liquid which is kept at the desired temperature by the steam-jacket, though it 80 is to be understood that the liquid may be introduced before the stock is in place on the drum as the stock may of course be readily led through the solution. It is obvious that when the drum is thus provided 85 with a loop of stock its perforated body is covered and closed by the stock and the bottom wall g of the guide whose beveled ends project between the drum and stock, and that the drum and recess at its end then 90 form a chamber from which the solution may be pumped and in which a reduction of the air pressure may be caused by more or less exhausting its interior by the pump P . If the tank is first filled with the liquid the 95 solution in the now closed drum may be drawn through the pipe a^6 , so that the outer surface of the stock is subjected to the penetrating force of the solution while its opposite surface is free from the direct contact 100 of the solution, and the same effect will be accomplished if the solution is discharged into the tank after the initial lead of stock is in place on the drum. If it is desired the 105 pump may be operated to more or less reduce the air pressure in the drum so that the suction thereby created will draw the solution through the stock; after the initial loop of stock is in place on the drum the 110 operation of the pump will reduce the pressure in the drum for the purposes described. In either case the drum is rotated to move the stock from the inlet roller to the outlet roller where it is fed out as indicated in 115 Fig. 1. The speed of the stock depends somewhat upon its density; for treating strawboard the drum is preferably of sufficient size to expose about thirty lineal feet of stock to the action of the liquid, and the drum will make about two revolutions per 120 minute, while for more porous stock its rate of speed may be increased. But in all cases the speed for any particular kind of stock is uniform so that all portions of it are subjected to the positive and direct action of the 125 liquid for approximately equal times to secure uniformity of saturation. The penetrating force of the liquid may be varied for stocks of different densities by increasing or decreasing the pressure of the body 130

of the solution on the outer surface of the stock by putting the solution in the tank under pressure, as for example by having the pump that draws from the interior of the drum discharge into the pipe a^2 ; and the 5 penetrating force may also be increased by reducing the air pressure in the drum, and this pressure may also be regulated so that the speed of charging the stock with the 10 solution may be increased. A pressure of two or three pounds to the square inch on the body of the solution in the tank will be sufficient to expedite the action, and the reduction of air pressure in the loop may be 15 varied for stocks of different density. Any excess of solution that may pass through the stock will drip into the drum and be carried off by pipe a^6 , and when the pump connects the pipes a^2 and a^6 the circulation of 20 excess solution will be carried out.

In the form of apparatus shown in Figs. 3 and 4, the tank is of increased depth, and the shaft d located at or near its bottom is provided with a series of spaced rings d^4 25 carried by corresponding spiders d^5 fixed or loose to the shaft, the two end rings being made with solid or imperforate heads d^6 . A suitable frame F is centrally supported in the tank above the drum and carries two opposite banks or groups of vertical ribs f spaced apart and arranged in line with the rings d^4 , the end ribs being flat and the intermediate ones being preferably formed by suitable T-bars, and all 30 having their lower ends f' beveled in correspondence with the curvature of the rings to closely contact therewith. A pair of endless wire-mesh belts or aprons E' and E^2 is provided with their operative runs located in the tank and extending in parallelism down and around the rings d^4 . The 35 upper portion of the inner apron E' is carried upon a pair of drive rollers e suitably journaled in bearings on the frame of the apparatus at opposite sides of the vertical guides, and the lower portion of this apron passes along the ribs and around the guide rings d^4 in contact therewith, it being understood that the guide rings merely form 40 supports for the lower stretch of the apron and that consequently in this form of the apparatus they may be made revolving or stationary as desired. The upper portion of the outer apron E^2 is provided with a 45 pair of drive rolls e located outside of the drive rolls for the inner apron E' , it being understood that all of these drive rolls are suitably driven by any desirable means so that the aprons will travel in unison. The 50 inner or operative run of the apron E^2 passes over an opposite pair of guide rolls e^3 which are located adjacent to the upper ends of the guides f and in such position as to hold the operative run of the apron E^2 55 in contact with the operative run of the

apron E' , and to hold this latter run against the guides f and the cover G . The idle run of the apron E^2 passes around a pair of idle rolls e^4 and thence down around the idle roll e^5 in the tank, the arrangement being such 70 that when the aprons are driven with a length of stock or material interposed between them as shown in Fig. 3 they will carry the latter down the length of one set of guides f around the rings or guides d^4 75 and up the length of the opposite set of guides f . The edges of the inner apron E' are provided with a suitable facing E^3 adapted to make close fit with the end guides d^6 and f so as to make the sliding contact 80 or joint between these parts tight enough to prevent the solution passing into the open space within the operative run of the apron E' and to enable the air pressure therein to be reduced when a length of material or 85 stock S is in place thereon, the similar sliding contact or joint between the cover G and the inner run of the apron E' being tight enough to permit this reduction of air pressure. The discharge pipe a^6 in this form of 90 the apparatus is extended upwardly between the guides f and through the cover, and it connects with a suitable pump P as shown in Fig. 5; the discharge of this pump may connect to the supply pipe a^2 of the tank. 95 When a length of stock is in position between the operative runs of the aprons as shown in Fig. 4 the operation of the pump will draw the solution from the space inside of the loop of stock, and as the stock 100 is carried along by the operative runs of the aprons its outer surface is subjected to the pressure or stress of the solution in the same manner as in the apparatus of Figs. 1 and 2 but to an increased degree owing to 105 the increased depth of the tank, and in a similar manner the air pressure within the loop or portion of the material under treatment between the operative runs of the aprons may be reduced by the exhaust action of the pump P to expedite the evaporation of the air, gases and moisture and to draw the solution into the stock or material. 110 The solution is positively forced into the stock, and so the saturation requires less 115 time than heretofore. The pressure upon or draft through the stock is uniform on all portions of it, and so the saturation is uniform and complete throughout the finished product. The air, moisture and gases are 120 drawn out of the stock and their places are taken by the solution, so when the product dries and sets the filling is homogeneous and the stock is free from puffs, blisters and similar deteriorating conditions. By my invention I can saturate dense stock, such as strawboard having a density or thickness of 125 .075 or .085, in less time than was heretofore required to saturate paper felts or similar goods made in part of rags, and as straw- 130

board makes a better product for shingles and building materials than those others and is a cheaper base being made from various kinds of straws which are annual products 5 in large quantities, my invention enables me to make denser grades of finished products even cheaper than the more porous grades were heretofore made. The stock is moved in a steady manner so that all sudden or intermittent strains and pulls on it are eliminated, each portion of the stock is suspended against the weight of the body of solution from the moment of its contact with the latter to its exit, and it is also supported 10 against the pressure of the solution to eliminate liability of its breaking if subjected to a pressure beyond the resistance of its tensile strength.

I may use any suitable asphaltic or bituminous solution, and I use the term "asphalt" 20 in my claims to mean any such solution; and I use the term paperboard in my claims to mean any of the known grades or types of such materials made in whole or in part 25 from paperstock, paperfelt, or pulpboards, chipboards, strawboards, etc.

I am aware that attempts have heretofore been made to saturate porous fabrics or 30 materials by immersing them in a bath of hot solution under such conditions that the material or fabric is carried to the lower portion of the tank where it is subjected to the pressure of the solution; for example, as in the patent to Beach and Wood, No. 35 241,118, dated May 10, 1881. But in all such instances the pressure of the solution is applied to both sides of the stock with the result that the air, steam and gases in the stock are trapped and held in it so that 40 they resist the passage or flow of the solution into the stock, with the result that the saturation is impeded, and as these foreign matters are unevenly scattered or spotted through the stock its saturation is extremely 45 uneven, whereas by my invention all these foreign matters are evacuated from the stock so that the saturation is expedited and uniform. I make no claim in the present case to the apparatus shown and described

herc in as the same forms subject-matter of 50 my application filed April, 15, 1918, and bearing Serial Number 228,528.

I claim:—

1. The method of saturating porous fabrics with liquid solutions which consists in 55 subjecting one surface of a traveling length of the stock to the weight of a body of the solution, and maintaining the opposite surface of the stock free from direct contact with the solution. 60

2. The method of saturating paperboard with asphalt which consists in subjecting one surface of a steadily traveling length of paperboard to the weight of a body of 65 asphalt solution, and maintaining its opposite surface free from direct contact with the solution.

3. The method of saturating paperboard with asphalt which consists in effecting the continuous travel of a length of paperboard 70 in the presence of a body of asphalt solution, subjecting one surface of the stock to the weight of the solution, maintaining its opposite surface free from direct contact with the solution, and reducing the air pressure 75 on said opposite surface.

4. The method of saturating paperboard with asphalt which consists in simultaneously suspending and moving a length of the stock in the presence of a body of asphalt 80 solution, subjecting one surface of the stock to the weight of the solution, and maintaining the opposite surface of the stock free from direct contact with the solution.

5. The method of saturating paperboard 85 with asphalt which consists in supporting and moving a length of stock in the presence of a body of asphalt solution, subjecting one surface of the stock to the weight of the solution, and maintaining its opposite surface 90 free from direct contact with the solution.

In testimony whereof I affix my signature in presence of two witnesses.
